(57)

CLAIM

The ornamental design for a combined tweezer and applicator for artificial lash extensions, as shown and described.

DESCRIPTION

FIG. 1 is a top left perspective view of a combined tweezer and applicator for artificial lash extensions, in accordance with the claimed design.

FIG. 2 is a bottom right perspective view thereof.

FIG. 3 is a left side view thereof.

FIG. 4 is a right side view thereof.

FIG. 5 is a bottom view thereof.

FIG. 6 is a top view thereof.

FIG. 7 is a front view thereof; and,

FIG. 8 is a rear view thereof.

1 Claim, 5 Drawing Sheets
